[57] CLAIM

The ornamental design for a combination tire pressure
and tread depth gauge, as shown and described.

DESCRIPTION

FIG. 1 is a front elevational view of the combination
tire pressure and tread depth gauge showing my new
design;

FIG. 2 is a rear elevational view;

FIG. 3 is a right side elevational view, the left side
elevational view being a mirror image;

FIG. 4 is a top plan view;

FIG. 5 is a bottom plan view; and

FIG. 6 is an enlarged fragmentary view thereof, show-
ing the tire tread depth and air pressure indicator of
FIG. 3.
